(57) **CLAIM**

The ornamental design for a handle for portable surgical device, as shown and described.

DESCRIPTION

FIG. 1 is an elevational view of a right side of a handle for portable surgical device in accordance with the present design;

FIG. 2 is an elevational view of a left side of the handle for portable surgical device of FIG. 1;

FIG. 3 is an elevational view of a rear side of the handle for portable surgical device of FIG. 1;

FIG. 4 is an elevational view of a front side of the handle for portable surgical device of FIG. 1;

FIG. 5 is an elevational top plan view of the handle for portable surgical device of FIG. 1;

FIG. 6 is an elevational bottom plan view of the handle for portable surgical device of FIG. 1;

FIG. 7 is a perspective view of the left side of the handle for portable surgical device of FIG. 1 from above the front thereof;

FIG. 8 is a perspective view of the left side of the handle for portable surgical device of FIG. 1 from below the front thereof;

FIG. 9 is a perspective view of the right side of the handle for portable surgical device of FIG. 1 from below the rear thereof; and,

FIG. 10 is a perspective view of the right side of the handle for portable surgical device of FIG. 1 from above the rear thereof. The broken line showing is for environmental purposes only and forms no part of the claimed design.
